UNITED STATES PATENT OFFICE.

CHARLES EDMUND KELLS, OF NEW ORLEANS, LOUISIANA.

TROCAR.

1,147,408.

Specification of Letters Patent.

Patented July 20, 1915.

Application filed February 8, 1915. Serial No. 6,781.

To all whom it may concern:

Be it known that I, CHARLES EDMUND KELLS, a citizen of the United States, residing at New Orleans, in the parish of Orleans and State of Louisiana, have invented certain new and useful Improvements in Trocars, of which the following is a specification.

This invention relates to surgical instruments of the kind called trocars which are used for withdrawing fluids of various kinds from the body, such as pus from a sac containing it. Trocars ordinarily comprise a lance or similar device used to puncture the sac or other part of the body and a tube or barrel in which the lance is inclosed and in which it is mounted to reciprocate in such manner that it may be drawn into the barrel or projected therefrom to pierce the sac or other fluid-containing part of the body. The tube or barrel is usually connected with a pump or other vacuum-producing device which serves to draw the pus or other fluid from the pierced part and causes it to pass into and through the barrel to a suitable receptacle. I have found that in the use of such instruments the fluid withdrawn from the body often leaks past the end of the barrel of the instrument and re-enters the body or passes into some cavity of the body adjacent to the part pierced. This is not only objectionable but is often dangerous.

The object of my invention is to overcome this fault, and I preferably do it by providing a sheath which surrounds the lower part of the barrel and is adapted to fit tightly against the sac or other part pierced by the lance in such manner as to prevent the escape of fluid from the instrument. The interior of the sheath communicates with the interior of the trocar barrel through an opening in the latter, and the arrangement is such that any extracted fluid which leaks past the end of the trocar barrel is caught by the sheath through which it is drawn into the barrel and thence passes through an outlet thereof. In this way, as I have demonstrated, leakage is absolutely prevented and when the trocar is withdrawn from the body no fluid is left behind which would otherwise be dangerous. The sheath is made adjustable to accommodate the part to which it is applied, and to make a close contact therewith.

I may also embody my invention in an in-

strument in which a puncturing device is mounted to reciprocate in a barrel connected with a vacuum-producing apparatus, and in which the puncturing device is made hollow, a chamber therein connecting by a lateral opening with the interior of the barrel, the arrangement being such that the inner end of the barrel may be placed in close contact with the part to be treated and any liquid which leaks past the interior of the puncturing device may be drawn into the barrel around the outside of the puncturing instrument.

In the accompanying drawings: Figure 1 shows a longitudinal central section through a trocar, embodying my improvements and showing how it is applied to the body on which it operates, and before the lance has been projected. Fig. 2 is a similar view, showing how the lance is made to pierce the part operated upon. Fig. 3 is a similar view, showing how the trocar barrel is made to enter the puncture made by the lance. Fig. 4 is a view on an enlarged scale, and in end elevation of the preferred form of lance. Fig. 5 shows a longitudinal central section through a modified form of the invention. Fig. 6 is a detail view of some of the parts shown in Fig. 5. Fig. 7 shows a longitudinal section of a modification.

The barrel A of the trocar may be of any suitable construction and of any suitable material. Near its outer end it is provided with a branch tube B which may be connected with any suitable vacuum-producing apparatus. The lance or puncturing device C may also be of any suitable form, its stem or rod c being passed through a cap b applied to the outer end of the barrel having preferably a threaded and packed connection therewith, as shown. The stem is provided with a handle c' by means of which the lance may be operated.

As thus far described the trocar is of usual construction, but as before stated when such an instrument is used there is apt to be leakage at x past the end of the barrel, and the fluid thus escaping is apt to enter some adjacent part of the body and cause blood poisoning or other injury. In order to prevent this I provide the trocar with a sheath D which may be made of any suitable material and which is preferably bell shaped as shown, and has a tight fitting but sliding connection at d with the barrel. The construction is such as to leave a chamber d'

between the sheath and the barrel while the outer edge of the sheath is adapted to make close fluid-tight connection with the body X operated upon. The outer end y of the 5 barrel is so formed that it may be passed through the puncture made by the lance and enter the cavity, in the manner indicated in Fig. 3. In order to establish connection between the chamber d' of the sheath and 10 the interior of the barrel a hole d² is made in the latter so that fluid caught in the sheath may pass therefrom into the barrel and thence pass through it with the fluid directly entering the barrel.

15 In use the instrument is applied to the body in the manner indicated in Fig. 1, the point of the lance being within the trocar barrel, the outer end of the barrel being in contact with the part to be pierced and the 20 outer edge of the sheath being pressed against the body, as indicated, so as to make a close fluid-tight connection therewith. When this is done the lance is pushed into the part treated and made to pierce it in 25 the manner shown in Fig. 2. Directly after this the trocar is pushed inward to a slightly greater extent until the inner end of the trocar barrel enters the puncture, in the manner indicated in Fig. 3, the trocar barrel at 30 this time sliding through the joint with the sheath at d. Most of the pus or other fluid in the sac or other part treated is drawn through the trocar barrel and out through the branch tube B. Any fluid that leaks or 35 escapes at x and passes to the outside of the trocar barrel will be arrested or caught by the sheath D and will be drawn through the opening d² in the barrel and pass out through the latter.

40 It will be understood that as soon as the parts are adjusted to the position shown in Fig. 1 the vacuum-producing apparatus is started and continues to act until the operation is completed. I have stated that any 45 suitable form of lance or puncturing device may be used, but preferably the lance is of the kind illustrated in order that the fluid may readily pass by way of the grooves e to the trocar barrel. Instead of providing 50 the trocar barrel with a branch tube B, I may provide the lance C, as shown in Fig. 5, with a tubular or hollow stem F, having at its outer end a part G which may serve as a handle and with which the vacuum- 55 producing apparatus may be connected, otherwise the instrument is similar to that before described, except that in this case the lance c is hollow and is provided with openings g, g' for establishing communication

between the outside of the lance and the interior of the tube F.

The details of construction may be further varied without departing from my invention which consists broadly in providing some means for preventing the escape of fluid 65 from the trocar.

In Fig. 7 I have shown an instrument consisting of a barrel end having a branch pipe m adapted to connect with a vacuum-producing apparatus, and a puncturing instrument N having a stem n passing through a packed cap O. The inner portion of the puncturing instrument is hollow, as shown, and communicates with the interior of the barrel through a hole o. The inner end of the trocar may be placed in close contact with the parts to be treated, and the vacuum-producing apparatus started. Then the puncturing instrument is pushed inward, and most of the fluid extracted is drawn 70 through the chamber x and through the hole o into the barrel and thence through the branch pipe m. As shown, however, there is a space y' between the barrel and the puncturing instrument, and any liquid which 75 does not enter the interior of the instrument or leaks past it is caught or arrested and drawn through the space y' into the barrel. Such an instrument may be used with 80 facility, although the instrument hereinbefore described is preferred.

I claim as my invention:—

1. A trocar, comprising a barrel, a lance mounted to reciprocate therein, means for conducting fluid from the part pierced by the lance, a sheath surrounding the inner end of the barrel, and a communication between the interior of the sheath and the barrel.

2. A trocar, comprising a barrel, a hollow puncturing device mounted to reciprocate therein, and means for withdrawing liquid from the part treated through both the puncturing device and the barrel.

3. A trocar, comprising a barrel, a puncturing device mounted to reciprocate therein, vacuum-producing apparatus connected with the trocar and receiving liquid from both the inside of the portion thereof entering the part treated and also from the outside thereof.

In testimony whereof, I have hereunto subscribed my name.

CHARLES EDMUND KELLS.
